 Filed May 16, 1962, Ser. No. 195,230
 6 Claims. (Cl. 198—24)

This invention consists of a device in machinery used for the sorting of all kinds of lumber and timber, particularly logs and the like. It comprises a dog conveyor consisting of dogs carrying the goods and moving along two adjacent rails, and longitudinally spaced log deposition stations or pockets on one or both sides of the conveyor to receive the sorted lumber. The device according to the invention is located at the point of each pocket so that the logs, etc. can be dropped straight into the desired pocket.

The principal feature of the invention is that a portion of one of the rails in the section of the conveyor adjacent to the pocket can be lowered so that the dogs on this section slope down in the direction of the pocket and drop the piece of the lumber or timber into it.

The purpose, advantages and other details of the invention will become clear from the following description and the attached drawings, in which

FIG. 1 is a vertical, longitudinal section of the device according to the invention along the line I—I in FIG. 2;

FIG. 2 shows the same as seen from above, and

FIG. 3 is an enlarged cross section along the line III—III in FIG. 1.

The dog conveyor in the drawing consists of dogs 2a and 2b driven by a chain 3 and moving along two fixed rails 1. In the embodiment presented, there are pockets or deposition stations, one of which is shown generally at 16, for sorted lumber on either side of the conveyor. Each pocket has its own device according to the invention. Since, therefore, two such devices lie adjacent to each other, only one need be described here. Logs carried by the conveyor rest in shallow concave seats 15 on two consecutive dogs 2a and 2b.

As shown in FIGS. 1 and 2, the fixed rails 1 end at the point where the pockets begin, and are replaced by two movable rails 4 hinged to the upper ends of two pairs of supporting rods 5 at points 6. At point 7 the lower ends of the rods are hinged to axles in the frame of the conveyor. When the device is in its upper position, the upper surface of the movable rails 4 is level with that of the fixed rails 1 and the supporting rods 5 slope slightly in the direction of conveyance, which is shown by arrows.

Near the rear end of the rails 4 are a trip lever 9 and a draw lever 10, both turning on a transverse axle 8 in the frame of the conveyor. To the underpart of the bushing of the trip lever 9 is attached a chain 11 the other end of which is attached to the upper part of the bushing of the rear supporting rod 5 in such a way that, when the movable rails are in their upper position, the chain is tight. An electric magnet 12 is fitted near the rear end of the movable rails 4. Under the magnet 12 is a hinged lever 13 which functions in conjunction with the draw lever 10, as explained hereunder.

Attached to and turning on the bushing of the supporting rod 5 at the front end of the movable rail 4 is a catch lever 14 the upper end of which lies below the surface of the rail 4 when this is in its upper position, and above it when it is in its lower position.

The device according to the invention functions as follows:

After the front dog 2a has passed over the trip lever 9, the electric magnet 12 is switched on so as to attract to it the end of the lever 13. This turns the draw lever 10 in a clockwise direction, thus also turning the trip lever into the line-and-dot position shown in FIG. 1. Thereupon, the rear dog 2b, in moving forwards, thrusts the release

2

lever 9 into the broken line position shown, so that it pulls the chain 11, turns the rear rod 5 in an anti-clockwise direction and causes the movable rail 4 to descend into the position shown by broken lines. Consequently, the dogs 2, which are supported by one rail in the upper position and one in the lower position, slope at the angle shown by broken lines in FIG. 3, and the log carried on them falls into the container. As the dogs move on, the lowered side of the dog 2b engages the catch lever 14, which is protruding above the rail on that side in the broken line position shown in FIG. 1. This turns the support rods 5 in a clockwise direction thereby raising the rail 4 into its upper position. When the rail 4 is in its upper position, the support rods 5 slope slightly in the direction of conveyance and the top end of the catch lever 14 remains a little below the upper surface of the rail 4, so that the dog 2b does not touch it on moving forwards.

The dogs 2a and 2b are set at such a distance that at the moment of drop they are both carried simultaneously by the rail 4. They should be made fairly tall so that when they turn, their centre of gravity will move rapidly to the side, thus accelerating the turn. If the device is used for sorting sawn timber, the upper edge of the dogs can be furnished with rollers to facilitate dropping.

Naturally, the invention is not restricted to the embodiment presented above. It can vary considerably within the limits of the claims. Furthermore it is equally applicable if there are pockets only on one side of the conveyor.

What I claim is:

1. Apparatus for the sorting of pieces of lumber and timber, particularly logs, comprising a conveyor extending along a plurality of longitudinally spaced log deposition stations on at least one side of said conveyor, said conveyor comprising two laterally spaced rails and a plurality of dogs movable on said rails for carrying said logs in their longitudinal direction at a level above said rails, a portion of said rail adjacent each of said deposition stations being separate from other portions of the rail, means for independently supporting said portions of the rail for movement in a vertical plane between an upper position level with other portions of said rail and a lower position below the other portions of said rail, for actuating the supporting means for said portion of said rail to lower it from said upper position to said lower position at the moment when dogs carrying a selected log are positioned on said rail portion, and means for automatically actuating the supporting means for said portion of said rail to raise it into said upper position after the selected log has been discharged into its deposition station.

2. Apparatus as claimed in claim 1, wherein the means for actuating the supporting means for said portion of the rail to lower it comprises a trip lever adjacent the entering end of said rail portion selectively movable into the path of movement of the dogs and retractable from said path, and means connecting the trip lever to the supporting means so that engagement of the lever by the dog actuates the supporting means to lower the said portion of the rail.

3. Apparatus as claimed in claim 2, wherein the means for automatically raising said portion of said rail comprises a catch lever adjacent the exit end of said rail portion and connected to said rail portion so as to extend into the path of the dogs when the said rail portion is lowered and to be retracted from the path of the dogs when the said rail portion is raised, the connection between the catch lever and said rail portion being such that engagement therewith by a dog causes the raising of said rail portion.

4. Apparatus as claimed in claim 3, wherein the means

for independently supporting said portion of the rail comprises a fixed support, at least two spaced parallel rods pivotally connected at their lower ends to the support, and means pivotally connecting the upper ends of the rods to the said portion of the rail.

5. Apparatus as claimed in claim 4, wherein the said portion of the rail is of such a length that there are only two successive dogs on it at a time.

6. Apparatus as claimed in claim 5, wherein the trip lever is connected to a first supporting rod, at the entering end of the said rail, so as to turn in the opposite direction from the turning of the said first rod about its

pivotal axis at its lower end, and wherein the catch lever is connected to a second supporting rod, at the exit end of the said rail, so as to turn with the second rod about its pivotal axis at its lower end.
